DESIGN FOR A GLASS DISPLAY CASE FOR DECORATIVE PURPOSES

Dixey Barry Carr, New York, N. Y.

Application March 11, 1942, Serial No. 106,157

Term of patent 3½ years

To all whom it may concern:

Be it known that I, Dixey Barry Carr, a citizen of the United States of America, residing in New York city, county of New York, and State of New York, have invented a new, original, and ornamental Design for a Glass Display Case for Decorative Purposes, of which the following is a specification, reference being had to the accompanying drawing, forming part thereof, wherein,

Figure 1 is a plan view of a glass display case

for decorative purposes showing my new design, and

Figure 2 is a top plan view thereof.

The essential features of my design reside in the specific ornamentations applied to the glass dome as shown.

I claim:

The ornamental design for a glass display case for decorative purposes, substantially as shown and described.

DIXEY BARRY CARR.
